UNITED STATES PATENT OFFICE.

JEREMIAH O'MEARA, OF NEW YORK, N. Y.

PENCIL-SHARPENER.

1,072,768.

Specification of Letters Patent.

Patented Sept. 9, 1913.

Application filed November 24, 1911. Serial No. 662,152.

To all whom it may concern:

Be it known that I, JEREMIAH O'MEARA, a citizen of the United States, residing at New York, in the county of New York and 5 State of New York, have invented a certain new and useful Improvement in Pencil-Sharpener, of which the following is a full, clear, and exact description.

The object of this invention is to provide a handy device for use in sharpening pencils, which is simple in construction, and may be economically made and sold.

The invention consists of a cutting blade, a holder therefor, and a shield applied to 10 the holder in such way that one may be moved upon the other to cover the cutting edge of the blade and so protect it and conceal it when the device is not in use, and to uncover it when it is desired to use the 20 blade to sharpen a pencil.

In the accompanying drawings illustrating the invention, in the several figures of which like parts are similarly designated, Fig. 1 is a perspective view. Fig. 2 is a top 25 plan view of the shield detached. Fig. 3 is a longitudinal section. Fig. 4 is a plan view of the knife and its holder, detached. Fig. 5 is a plan view of a modified form 30 of sharpener. Fig. 6 is a plan view looking at the side opposite to that uppermost in Fig. 5. Fig. 7 is a plan view of the blade and its holder of the modified form. Fig. 8 is a longitudinal section of the said modified form.

As shown throughout the drawings, the 35 blade 1 may be a flat rectangular piece of metal sharpened on one edge, or on parallel edges. As shown in Figs. 1 to 4, 2 is the metal holder, formed of a thin flat sheet 40 of metal and having one end 3 of reduced width, with portions of its sides turned over to form pockets 4, and these pockets are closed in at 5 to form stops for positioning the blade with relation to the edge of the 45 holder when said blade is inserted flatwise and frictionally held in said pockets, and to hold the blade in place especially when in use. The outer free ends of the pockets may be pointed so as to facilitate the insertion 50 of the blade. 6 is the shield also formed of thin flat sheet metal and having a body portion substantially co-terminous with the body portion of the blade holder 2, and provided with clips 7 forming pockets into 55 which the blade holder is slipped so as to connect and guide the blade holder and

shield in relative movement; and this movement of the parts one upon the other may be further limited by means of a rivet or other fastening device 8, inserted in slots 9 and 60 10, respectively, in the blade holder and shield. The rivet may be secured to one of the parts and play in a slot in the other. The forward end of the shield is reduced to substantially the greatest width of that portion of the blade holder in which the blade is secured, and may be offset as shown in Fig. 3, to accommodate the blade and blade holder. As shown in full lines in Figs. 1, 2 and 3, the shield is moved into position 70 of non-use, while in Fig. 1 the dotted lines show the shield moved so as to uncover the blade for use.

In the modified form shown in Figs. 5 to 8, the blade holder 11 has the pockets 12 to frictionally receive the blade 1, and it also has the clips 13 to receive the shield; and in addition, there may be a rear extension 14 having clips 15 to receive and secure a wiping device 16, of textile fabric or other material. This blade holder may also have additional blade positioning stops 17 in the form of rivets. The shield 18 has the clips 19 which overlap the blade holder next to the blade so that the blade holder and shield 85 are held by a duplex arrangement of clips. In addition, the blade holder and shield may be secured by a rivet 20 passed through slots 21 in one or both of them.

By grasping the blade holder and shield 90 between the fingers and thumb and moving the fingers and thumb in opposite directions, the blade holder and shield may be similarly moved to cover or uncover the cutting edge of the blade, as desired.

The blades in the two forms of the invention shown may be taken out and replaced at pleasure; and if parallel edges of the blade are sharpened, the blade may be easily reversed so as to present a fresh edge.

While I have shown two modifications of the construction of my pencil sharpener, it is obvious that other changes may be made within the scope of the invention.

What I claim is:

1. A pencil sharpener, comprising a cutting blade, a blade holder constructed of thin flat sheet metal and having turned over portions on one end forming pockets to receive and frictionally hold the blade, and provided with stops to retain the blade in position, a shield constructed of thin flat sheet

metal mounted upon one side of the blade holder and lying over the blade and its receiving pockets, and integral clips connecting the blade holder and shield to permit the shield to be moved lengthwise of the holder to cover and uncover the cutting edge of the blade.

2. A pencil sharpener, having a cutting blade, a blade holder constructed of thin flat sheet metal provided at one end with turned over portions forming pockets to receive and frictionally hold the blade, and stops to position the blade in said holder, and a shield constructed of thin flat sheet metal substantially coterminous with the

blade and blade holder and fitted upon one side of the blade holder over the blade and its receiving pockets, and integral clips movably connecting the blade holder and shield whereby the shield may be slid upon the 26 blade holder to cover and uncover the cutting edge of the blade.

In testimony whereof I have hereunto set my hand this 21st day of November A. D. 1911.

JEREMIAH O'MEARA.
